LITHOGRAPH-DRYING SYSTEM.

Application filed January 20, 1922. Serial No. 530,645.

To all whom it may concern:

Be it known that I, JULES A. NY, a citizen of the United States, and a resident of the city and county of San Francisco and State of California, have invented a new and useful Lithograph-Drying System, of which the following is a specification.

This invention relates to apparatus for printing or lithographing and continuously drying sheets of material and particularly relates to a combined apparatus for system including a printing or lithographing machine and a drying or baking oven the latter designed to receive the sheets or pieces of material as they are printed and issued from the printing or lithographing machine.

In the art of lithographing or printing especially sheets of tin or other metallic bodies the sheets are continuously fed into a printing or lithographing machine and issued therefrom onto a related conveyor or apron from which they are removed into an adjacent baking or drying apparatus through which the sheets are continuously advanced for a predetermined length of time and subjected to a suitable degree of temperature to facilitate the drying of the material on the plates or sheets. As at present practiced there is no co-ordinate relation between the printing machine and the drying apparatus and it is necessary for an attendant to stand at the machine to control the discharge of the sheets or plates into the drying apparatus to prevent them from becoming overlapped or injured as they are moved to a conveyor or drying rack movable through the drying apparatus.

It is therefore one of the objects of the present invention to provide an organized system including a lithographing or printing machine for treating metallic sheets or other plates to produce thereon the desired surface matter as for instance illustrations, labels and other data and to continuously feed the sheets as they are printed from the machine to a traveling rack movable through a drying or baking oven and to move the drying rack in synchronized relation and time with respect to the delivery of the plates from the printing or lithographing machine.

A further object of the present invention is to provide for the facile control of the independent operation of the printing ma-

chine and the drying rack or conveyor as is rendered necessary because of a frequent interruption of the operation of the printing or lithographing machine which must be done without interrupting the operation of the traveling rack moving through the drying apparatus.

A further object of the present invention is to provide a unitary system of control whereby power may be independently applied to either of the essential machines of the organization, that is, to the printing or lithographing machine, or to the drying apparatus.

A further object of the invention is to provide for the efficient control of the operation concurrently of the lithographing or printing machine and the drying apparatus and for the driving of the same from a common motor and further to provide an independent motor for driving one of the elements of the apparatus while the other may be idle, and in this connection it is a further object of the invention to provide a machine for continuously printing or lithographing a plate in combination with the drying apparatus and associated therewith by a common drive means for synchronizing the operation and to eliminate the requirement of an attendant whose services are ordinarily utilized in watching the discharge of the printed plate from the apron of the printing press into the traveling conveyor or rack which moves through the baking oven.

With these and other objects in view as will be rendered manifest from the following specification the invention consists of the construction, the combination, and in details and the arrangement of the parts, an embodiment of which invention is illustrated in the accompanying drawings, wherein;

Figure 1 is a side elevation showing diagrammatically the organized system including a lithographing machine and a baking apparatus including a traveling conveyor or rack with a synchronizing mechanism connecting the same.

Figure 2 is a plan view showing diagrammatically the system certain of the parts being broken away to illustrate more clearly the details of construction.

In the illustrated embodiment of the invention a type of lithographing or printing apparatus is diagrammatically indicated as

including printing rollers or cylinders 2-3 arranged upon a bearing conventionally shown at 4 and in which is mounted a shaft 5 that is provided on its outer end with a 5 pulley wheel 6 or other suitable means for deriving power from any appropriate motor, in this case the pulley wheel being driven by a belt 7 extending to a pinion pulley wheel 8 on the shaft of a motor 9, in this 10 case of the electrical type. Such a form of lithographing or printing machine is well known and is therefore only diagrammatically illustrated herein.

The plates or sheets that are to be printed 15 or lithographed are successively introduced into the printing machine and, passing through the same, are discharged to the usual apron or conveying system or belt 10 from which they are transferred to a suitable 20 form of carrier entering a baking oven or chamber 11 all of which is of well known construction and here diagrammatically shown.

The conveyor or rack, to which the plates 25 P pass from the apron belt of the press, generally comprises a set of sprocket chains operative over sprocket wheels secured on a shaft 12 extending across one end of the baking oven 11; these sprocket chains being 30 arranged in parallel relation and having attached in transverse position at suitable regular intervals receiving racks or frames of any suitable form of construction and shape and here indicated as U-shaped members 13, the ends of which are so secured to the respective sprocket chains 14 that those of the carrier frames 13 passing over the upper parts of the sprocket wheels 15 incline slightly rearwardly with respect to 35 the direction of travel so that the plates P thereon will remain in an upright and stable condition so as to prevent the marring of the printed or lithographed surface.

Heretofore there has been co-ordinate relation or co-action between a time of delivery of the printed plates or sheets from the press and the rate of movement of the conveyor carrying the printed sheets through the oven and for that reason the 45 presence of an attendant has been necessary so as to properly transfer the printed plates to the rack frames 13 and to prevent them from overlapping and piling upon one another on the frames.

To overcome this necessity one of the 55 purposes of the present invention is to co-ordinate and synchronize the motion or time of operation of the press and the rack or carrier so as to obviate the necessity of the attendant and to that end a driving connection is introduced between the press and the conveyor or carrier moving in the oven. One form of such transmitting connection is shown as including a gear wheel 16 secured 60 on the shaft 12 and which may be secured

in a housing or box 17 to guard against accident. The gear 16 is here shown as being of the worm type so as to engage and properly mesh with a worm 18 provided on a worm shaft 19 that is approximately journaled in bearings 20 as, for instance, on the lower part of the gear guard or box 17. Connected to the worm shaft 19 by a universal joint 21 is an extension or intermediate section shaft 22 that is universally jointed at 23 to the adjacent end of a short shaft 24 journaled in a box or bearing 25 and on which shaft 24 is formed or provided a gear 26. The gear 26 meshes with a complementary gear or pinion 27 that is provided on a shaft 28 mounted in suitable bearings 29 and 30 and which is here shown as extending transversely of the apparatus as a whole and as parallel to the driving shaft 5 of the lithographing machine and to the shaft 12 of the conveyor of the baking oven 11. However, it is to be understood that this arrangement of driving connections is but illustrative of an embodiment of the invention and is not intended to be limitation as to the arrangement or organization of the parts.

On shaft 28 is loosely but non-slidably mounted a sprocket wheel 31 engaging a sprocket chain 32 extending to the shaft 5 of the printing machine and engaging a sprocket pinion 33 secured thereon so that power is transmitted from the shaft 5 through the sprocket connections to the shaft 28 if the sprocket wheel 31 be clutched to the shaft 28 as will now be described.

The sprocket wheel 31 has at one side a projecting hub portion 34 provided with a clutch face 35 adjacent to a clutch sleeve 36 that is splined on shaft 28 and which may be thrown into and out of mesh with the clutch face 35 at will by the operator as through the manipulation of a control lever 37 having suitable co-operation with the sleeve or clutch member 36.

From the above it will be seen that there is provided a driving connection between the main shaft 5 of the printing or lithographing machine and the end shaft 12 of the carrier which carries the plates into the oven 11 and that by means of the clutch 36 the operation of the shaft 12 through the transmitting sprocket chains 32 and its wheel 31 may be interrupted so that the printing or lithographing machine can be operated without driving the carrier or rack passing into the oven 11.

But it is desirable that means be provided for continuously operating the rack or conveyor which is carrying plates into the baking or drying oven independently of the fact whether or not the lithographing or printing machine may be in operation and to that end a feature of the present invention resides in the combination of a supple-

mentary or auxiliary motor or other suitable power applying means that can be connected at will to operate the carrier passing into the oven.

- 5 This independent drive is accomplished preferably through the utilization of a driving means connectible at will to the intermediate shaft 28 and a form of such means is shown as including a transmission of mechanism between the shaft 28 and an auxiliary driver, as for instance a motor 40, that may have secured on its shaft a sprocket pinion 41 engaging a sprocket chain 42 which is extended to and engages a sprocket wheel 15 43 loosely but nonslidably mounted on the intermediate shaft 28 so that this shaft may be driven by the connecting means, for instance sprocket chain 32 from the main shaft 5, or it may be driven from the motor 20 40 if the sprocket wheel be locked to the shaft 28 which may be done by throwing the clutch 36 into interlock with the adjacent clutch face 44 formed on the adjacent end of the wheel 43.
- 25 From this it will be seen that the invention provides a single clutch member having the dual function of selectively connecting the intermediate shaft 28 either to the main shaft 5 to be driven by the same or to the 30 transmission means of the motor 40 in which latter case the plate rack or conveyor may be continuously operated through the oven 11 irrespective of whether the press is in operation or not.
- 35 In the operation of the present system the pressman or other person in charge of the apparatus when starting the press watches the discharge of the plates P therefrom and the passage of the same onto the intermediate 40 apron or belt 10 so that at the moment that a plate passes from the intermediate apron to one of the frames 13 of the rack conveyor, the main clutch 36 can be thrown into mesh with the clutch face 35 of the 45 sprocket wheel 31 at the instant that a space is presented, at the discharge end of the apron means 10, between a pair of the frames 13 with the result that the plates will be properly introduced into the intervening 50 space and thereafter the successive discharge of the plates from the press and their discharge by the apron conveyors 10 will be synchronized to feed the plates successively into the intervening spaces between the successive frames 13 forming the 55 oven conveyor.

It is obvious that since the press and the oven carrier are now synchronized by the connecting drive means the speed of the 60 press may be increased and coincident with this the speed of movement of the oven carrier will be increased in proper time and synchronously because of the positive drive connections between the two machines, that 65 is, the press and the drying apparatus.

It is therefore possible for the pressman or operator to interrupt the operation of the lithographing or printing machine at any time by stopping its motor 9 and then throwing in the connection between the auxiliary driving means or motor 40 and the intermediate shaft 28 so that the operation of the plate carrying rack may be continued independently of the drive of the press.

A further advantage of the present organization is that the co-related press and the oven mechanism may be concurrently driven by power derived from a single source as for instance the main motor 9 as contra-distinguished from the now common system of driving the press and the oven shaft conveyor by independent means operative without co-ordination or synchronism.

It is understood of course that the present disclosure is but one embodiment of the apparatus parts of which may be reconstructed and varied in organization and arrangement of the parts and that may be adapted to different types of machines and baking ovens or systems as expediency may require, and further it is understood that any suitable form of connecting means as between the press drive and the conveyor drive may be designed and organized within the spirit of the invention and scope of the appended claims.

What is claimed is:

1. A system for continuously printing and drying bodies, comprising, in combination, a printing machine; a drying apparatus including a traveling conveyor to receive the bodies successively from the machine, means for synchronizing the action of the machine and the conveyor and means for interrupting the operation of the synchronizing means so that the machine and the conveyor may be independently driven or stopped.

2. A combined printing or lithographing machine and drying apparatus including a conveyor with synchronizing drive means connecting the same to secure timed discharge of printed bodies from the one to the other and for eliminating interference of transferred, printed bodies, separate drive means for the machine and the conveyor, and selective means for connecting one of the drive means to the synchronizing means.

3. A combined printing or lithographing machine and drying apparatus including a conveyor with synchronizing drive means connecting the same to secure timed discharge of printed bodies from the one to the other and for eliminating interference of transferred, printed bodies, separate drive means for the machine and the conveyor, and selective means for connecting one of the driving means to the synchronizing means and disconnecting the separate drive means for the machine.

4. A combined printing or lithographing machine and drying apparatus including a conveyor with synchronizing drive means connecting the same to secure timed discharge of printed bodies from the one to the other and for eliminating interference of transferred, printed bodies, separate drive means for the machine and the conveyor, and selective means for connecting one of 10 the driving means to the synchronizing means and disconnecting the other so that each drive means may be operated irrespective of the other.
5. A combined printing or lithographing machine and a drying apparatus, including a conveyor to receive the printed bodies from the latter and take them through the apparatus; a drive shaft for the machine; a shaft for the conveyor; an intermediate 20 shaft; driving mechanism between the said drive shaft and the intermediate shaft; an auxiliary driver for the intermediate shaft; means for selectively connecting and disconnecting said mechanism and said intermediate shaft so that the former can operate independently, and for connecting and disconnecting the auxiliary driver to the intermediate shaft alternately as to the drive shaft; and means connecting the intermediate shaft to the drive shaft of the conveyor to drive the latter with or independently of the drive of the printing machine.
6. A combined printing or lithographing machine, and a drying machine; two independent sources of power, means for providing synchronous operation of both ma-

chines from one source of power, and means for driving said drying machine from said other source of power independent of said last mentioned means.

7. A combined printing or lithographing machine, and a drying machine; two independent sources of power, synchronizing driving mechanism connecting the two machines to insure unison of operation, selective means for connecting said synchronizing driving mechanism to one of said sources of power, and selective means for independently driving said drying machine from the other source of power.

8. A combined printing or lithographing machine, and a drying apparatus including a conveyor; a driver for the machine, a driver for the conveyor, a synchronizing mechanism connecting the machine and the conveyor, and means for disrupting said synchronizing mechanism and to connect the driver for the conveyor, or conversely for disconnecting the driver for the conveyor and operatively connecting said synchronizing mechanism.

9. A combined printing or lithographing machine and drying apparatus; driving means for said machine, drive gear connected to said drying apparatus, clutch means for positively connecting said driving means with said drive gear, and independently operable driving means for said drying apparatus.

In testimony whereof, I have hereunto set my hand.

JULES A. NY.
